BILL FOLD AND PURSE

Yukichi Miyeno, South Omaha, Nebr.

Application September 14, 1934, Serial No. 744,001

4 Claims. (Cl. 150—38)

This invention relates to improvements in purses or bill folds, particularly the pocket type.

An object of the invention is to provide a purse wherein a great variety of objects such as cards, photographs, postage stamps, receipts, paper money and coins may be easily and conveniently carried in separate compartments and in removable purse sections, without objectionably increasing the bulk of the purse and whereby to facilitate ready access to or several of such objects.

Another object is to provide a purse such as described wherein a comparatively great storage capacity is available in a relatively small and compact purse of the book folding type and which remains comparatively flat and may be comfortably carried in the vest pocket when filled to capacity.

A further object is to provide a purse pocket book such as described which will eliminate guess work in looking for papers and cards etc. stored therein, due to the provision of compartments and removal sections especially adapted and constructed to receive certain of the objects, paper, money, etc. such as usually carried in pocket books, and also due to constructions and arrangements permitting of readily viewing the contents of such compartments and sections upon opening the purse.

Another object is to provide a purse wherein certain sections or compartments are independent of the purse proper and are removably carried in other compartments whereby to insure a safe and individual carrying of money, etc., while at the same time increasing the capacity of the purse, there being in effect, a series of small purses within a large or main purse.

Yet another object is to provide a purse such as described wherein the several smaller purses which are removable from the purse proper are joined to the latter in an ingenious manner permitting of free access thereto while preventing loss thereof, the means of joining the "purses" insuring the replacement of the removable purses in the proper place therefor in the main purse.

The invention possesses other objects and features of advantage, some of which, with the foregoing will be set forth in the following description of the preferred form of the invention which is illustrated in the drawing accompanying and forming part of the specification. It is to be understood, however, that variations in the showing made by the said drawing and description may be adopted within the scope of the invention as set forth in the claims.

Referring to the drawing Fig. 1 is a top plan view of the purse as when opened.

Fig. 2 is a perspective view showing the purse opened and folded back to reveal compartments and removable sections thereof.

Fig. 3 is a sectional view taken on the plane of line 3—3 of Fig. 1.

Fig. 4 is a view similar to Fig. 3 showing the removable purses, withdrawn from the purse proper.

Fig. 5 is a perspective view of one of the removable purses showing small removable purses stored therein.

Fig. 6 is a perspective view of another of the removable purses designed to hold coins.

Fig. 7 is a perspective view of one of the sections of the purse shown in Fig. 5.

One embodiment of the invention as shown in detail in the accompanying drawing, comprises a main purse or body portion arranged to fold like a book and which is adapted to contain removable purse or purse sections 2 and 3, the latter of which contains two removable sections or smaller purses 4 and 5. It is thus seen that the purse as a whole comprises a plurality of purses with a main purse with each purse or purse part, peculiarly adapted to contain the object usually carried in purses such as cards, small photos, receipts, paper money, coins, postage stamps, license and lodge cards, etc.

The purse proper comprises a body piece 6 of leather or the like of rectangular form, doubled back as at 7 half its length and stitched as at 8 and 9. This forms a large compartment which is divided into compartments 10 and 11 by a partition piece 12 secured by the stitching 8 and 9. The compartment 10 is adapted to receive the removable purse 2 whereas the compartment 11 receives the removable purse 3.

The other half of the purse proper is formed as jacket 12a for cards, papers, money, etc. by stitching as at 13 a piece 14 to the body piece 6, at the corners of this piece 14 are small jackets 15 into which the corners of a card or photograph 16 are inserted whereby to hold the latter in place.

As here shown the removable purse 2 is formed as a flat rectangular receptacle closed at the margins and on all sides except for a narrow slit type opening 17 which prevents coins and the like placed in the receptacle from dropping out yet facilitates removal thereof.

Paper money and the like may when folded into small compass be placed in this purse. To prevent loss of this removable purse and to insure

its replacement in the compartment therefor a strap 18 is secured thereto and to the outer edge of the partition piece 12 whereby the removable purse may be withdrawn as shown in Fig. 4 and manipulated to remove coins, etc. therefrom or have the latter placed therein.

The largest removable purse 3 is comprised of two compartments 19 and 20 which are open along on longitudinal edges thereof, and a third compartment 21 which has a diamond shaped opening 22 on one outer side of the purse. The other outer face of side of this purse has a V-shaped cut 23 therein whereby to reveal a card or picture as shown at 24, there being a flexible transparent piece, if desired to cover the revealed portion of the card or picture 24.

Within the compartment 21 are the two small purses 4 and 5 each having two compartments opening at one edge thereof and each also formed 20 with a V shaped opening 25 in one outer side to reveal the presence of a postage stamp, coin or paper money may be placed in these small purses. These small purses are readily placed in the compartment and removed therefrom 25 through the diamond shaped opening 22.

Secured at one end to the purse 3 at the open edge thereof as at 29 is a strap 30 corresponding to the strap 18. The other end of this strap is secured to the partition 12 whereby to permit 30 of withdrawal of the purse 3 as shown in Fig. 4. This arrangement permits of full access to either side on the open edge of the purse 3 as the strap 30 is large and can be twisted as necessary to turn said purse around. Yet it is required that the 35 open edge of the purse 3 be inserted first and insures the replacement of the purse in the proper compartment. It also insures that the purse 3 will be inserted in place with the V shaped opening uppermost whereby to reveal the contents of one of the compartments of the purse, there being a V shaped opening 32 in the folded over piece of the body 6. These openings form a diamond shaped opening as noted in Fig. 1, through which latter certain contents of the 45 purse are readily visible without withdrawing purse 3.

It is apparent that the purse of this invention will provide the advantages hereinbefore noted in a particularly efficacious manner.

50 The construction and arrangement of the purse may be well adapted to hand bags, etc. and is therefore not limited to men's purses, bill folds and the like.

I claim:

1. In a purse, a purse proper of the book folding type and including compartments, a plurality of independent purses removably contained in said compartments and other independent purses removably contained in at least one of the first named removable purses, and certain of said purses having complementary openings to reveal contents thereof without requiring removal thereof of one from the other. 5

10 2. In a purse, a purse proper of the book folding type and including compartments, a plurality of independent purses removably contained in said compartments and other independent purses removably contained in at least one of the first named removable purses, certain of said purses having complementary openings to reveal contents thereof without requiring removal thereof of one from the other, and flexible tie straps 15 joining certain of the removable purses with the 20 purse proper.

25 3. In a purse, a purse proper of the book folding type and including compartments, a plurality of independent purses removably contained in said compartments and other independent 30 purses removably contained in at least one of the first named removable purses, certain of said purses having complementary openings to reveal contents thereof without requiring removal thereof of one from the other, flexible tie straps 35 joining certain of the removable purses with the 40 purse proper, and said straps being fastened within the compartments which are designed to receive the purses secured thereby.

4. In a purse, a purse proper of the book folding type and including compartments, a plurality of independent purses removably contained in said compartments and other independent purses removably contained in at least one of the first named removable purses, certain of said purses 45 having complementary openings to reveal contents thereof without requiring removal thereof of one from the other, flexible tie straps joining certain of the removable purses with the purse proper, said straps being fastened within the 50 compartments which are designed to receive the purses secured thereby, and being arranged in such manner as to require the open edge of one of the removable purses to be first inserted into the compartment for said one purse. 50

YUKICHI MIYENO.
